UNITED STATES PATENT OFFICE.

SAMUEL W. REYNOLDS, OF WEST TOLEDO, OHIO.

SPOT-SETTER.

No. 926,287.

Specification of Letters Patent.

Patented June 29, 1909.

Application filed May 8, 1907. Serial No. 372,594.

To all whom it may concern:

Be it known that I, SAMUEL W. REYNOLDS, a citizen of the United States, residing at West Toledo, in the county of Lucas and 5 State of Ohio, have invented a new and useful Improvement in Spot-Setters, of which the following is a specification.

My invention relates to improvements in spot setters.

10 This invention has for its primary object a device of its kind which can be used to set spots or rivets of various sizes and designs upon the surfaces of leather or other suitable material by hand at suitable distances apart 15 with accuracy and precision.

Further objects are simplicity of construction and effectiveness in use, thus rendering the device inexpensive and easy to manipulate.

20 Generally speaking, my invention comprises a suitable anvil frame on which a spring arm is carried, and a hand-operated setter which is adapted to pass through said frame and secure spots or rivets to the leather, 25 or other material at random or fixed spaces apart.

My invention further consists of the features of construction and combinations of parts hereinafter more particularly described 30 and claimed.

In the accompanying drawings, forming part of this specification, Figure 1 is a plan view of my invention, Fig. 2 is a side view of Fig. 1 showing the setter tool partly broken 35 away; Fig. 3 is a sectional view of one of the thimble holders; Fig. 4 is a plan view of said thimble holder; Fig. 5 is an enlarged detail sectional view showing the setter tool in the act of driving a spot through a strip of leather 40 or other suitable material; Fig. 6 is another sectional view showing the parts in position when a spot or other rivet has been secured to the leather or other suitable material, and Fig. 7 is a side view of one of the spots.

45 In the drawings A represents a suitable anvil frame and B a swinging arm above said anvil frame which is pivoted thereto at C between the posts 2. The swinging arm is formed with two or any suitable number of 50 openings 3 and 4 which are adapted to receive thimble holders for spots or rivets such as illustrated by 5 in the forward opening 3. These thimble holders may be of various sizes and designs so as to set spots or rivets 55 of corresponding shapes and sizes. The form of thimble holder shown is adapted for set-

ting the creased circular headed spot shown in Fig. 7, but it is obvious that this invention is equally applicable for use in setting any shaped spot or rivet desired. The object of 60 forming the arm B with two places for receiving the thimble holders is so as to increase the range of sizes to which the setter is applicable. The opening 3 as illustrated is adapted to receive thimble holders of three 65 different sizes and the opening 4 to receive thimble holders of three other larger sizes. These thimble holders are provided with a circular shoulder 6 which is received upon an edge surrounding one of its openings 3 or 4. 70 The inner wall of the upper end of the thimble holder is provided with downwardly and inwardly inclined slots 7 by which the shanks 8 of the spot are received and guided into the thimble and the spots held from turning. 75

The thimble spot holders are held in the openings 3 and 4 by means of thumb screws 9 which impinge against the outer walls of the thimble spot holders through the swinging arm to hold said holders in place. The 80 opening 10 in each thimble spot holder as shown is substantially cylindrical in shape and adapted to receive a cylindrical or other shaped set tool D of any suitable size therein. The lower portion of each set tool corresponds in diameter with the inner diameter 85 of the opening in its thimble holder mate and is provided with a recess 11 in its end for the purpose of forming a circular edge 12 which impinges against the circular edge of the 90 head of the spot to attach the latter to the leather. The depth of the recess is sufficient to space the set tool away from the head of the spot or rivet, thus avoiding all danger of marring or injuring the surface of such 95 head. It is obvious that the set tool may set firmly over the entire surface of the head when desired.

Immediately below the thimble holder in the anvil frame A are three concentric 100 grooves 13, the larger one coinciding with the lower end of the thimble spot holder immediately above it and the next smaller and smallest grooves coinciding respectively with the smaller thimble spot holders when used 105 and in a similar manner as the first one. These grooves appear in cross section as curved so as to guide and turn inward the shanks 8 of the spot on the lower side of the leather when the set tool is driven home. 110

Between the anvil frame and the swinging arm B is a longitudinal gage E the face plate

14 of which is carried upon a longitudinal rod 15 which passes through the end 16 of the anvil frame and is set in longitudinally adjusted position by means of the thumb bolt 17, the inner end of which impinges against said rod. The lower edge of the face plate 14 rests upon the anvil frame and thus prevents the rod 12 turning and is provided with a dovetail groove 18 traversing its face 10 in which a transverse gage F works, the latter being held in adjusted position by means of the screw 19. The transverse gage is spaced above the anvil frame so that the leather and the spots which are set thereon 15 are free to pass below it, without interfering. With these gages described, the spots or rivets can be set in a row and equally spaced apart in a quick and effective manner. The rod 15 and gage F may be provided with scales 20 (not shown) to facilitate setting the gages.

In use the thimble holder corresponding in size with the spots or rivets which are to be set is placed in the swinging arm B and fastened by means of one of the set screws 9. 25 The gages E and F are then set adjacent to the thimble holder so as to properly guide the leather below said holder and space the spots or rivets equally apart. The spots or rivets are then placed one at a time in the 30 holder and the set tool driven home through the thimble, thus setting the spot or rivet with its shanks passing through and engaging the leather or other material.

In accordance with the patent statutes, I 27 have described the principle of operation of my invention, together with the apparatus which I now consider to represent the best

embodiment thereof, but I desire to have it understood that the apparatus shown is only illustrative and that the invention can be 40 carried out by other means and applied to uses other than those above set forth within the scope of the following claim.

Having described my invention, what I claim as new and desire to protect by Letters 45 Patent, is:—

A device of the class set forth, comprising, in combination, an anvil frame having a swinging arm pivoted thereto in a plane above the same and provided with a plurality 50 of openings, thimble holders of different sizes in said openings and having circular shoulders resting on the edges of said openings and longitudinal slots in their walls to admit the shanks of spots to prevent them 55 from turning, thumb screws through the walls of the frame and impinging against the thimble holders to hold the latter, said holders being adapted to be mated with set tools having deep recesses, a rod passing longitudinally through the end of the anvil frame, a main gage plate having a transverse groove in its face carried by said rod, a transverse gage on said main gage and in said groove, and set screws holding said rod and 60 transverse gage in set positions, for the purposes specified.

In testimony whereof, I have signed my name to this specification, in the presence of two subscribing witnesses.

SAMUEL W. REYNOLDS.
